UNITED STATES PATENT OFFICE.

ORLAND D. ORVIS, OF CHICAGO, ILLINOIS.

HYDROCARBON-FURNACE.

SPECIFICATION forming part of Letters Patent No. 288,477, dated November 13, 1883.

Application filed May 25, 1883. (No model.)

To all whom it may concern:

Be it known that I, ORLAND D. ORVIS, a citizen of the United States, residing in Chicago, county of Cook, and State of Illinois, have 5 invented certain new and useful Improvements in Hydrocarbon-Furnaces, of which the following is a specification.

This invention relates to improvements in hydrocarbon-furnaces, in which hydrocarbons 10 have been injected into the fire-chamber by means of a steam-jet, or the combined force of a steam-jet and force-pump, in conjunction with air, said fire-chamber containing a permanent or temporary bed of coal or other solid car- 15 bonaceous fuel.

The objection to furnaces in which hydrocarbons have been heretofore employed in connection with a permanent bed of fuel are that steam is principally relied on for vaporizing the hydrocarbons and forcing them into the fire-chamber, when, as a matter of fact, it is capable of vaporizing only their very lightest portions, and of forcing the heavier and liquid portions but slightly in advance of the nozzle, 25 and as a result these heavier and liquid portions are thrown or drip down upon the bed of fuel, so that even such as are not totally lost by escaping through the grate-bars into the ash-pit are not fully utilized, owing to their 30 partial ignition, in consequence of which they produce a dense smoke and other noxious un-ignited gases. Without regarding the advantages of spreading the combined jet over the fire-chamber, these objections are increased by 35 a failure to combine proper proportions of air and steam with the hydrocarbons, and to inject into the fire-chamber even so much of the jet as is confined with sufficient rapidity and force to obtain the best results. Feeding 40 hydrocarbons by means of the combined force of steam and a force-pump along continuous and gradually-descending tortuous passages to outlets of a generator arranged in a fire-chamber is liable to result in the escape of liquid 45 portions of the hydrocarbons; and the attempt to combine heated air with such a stream near its point of exit cannot produce the best results, for the reason that a thorough admixture is impossible, and that the air is so rarefied 50 as to prevent the proper proportion of oxygen with the steam and hydrocarbon, even if com-

bined. Besides, such construction does not contemplate the use of a permanent bed of fuel, and effectually prevents it by reason of the tortuous-passaged generator occupying a 55 substantial portion of the fire-chamber. In another instance a retort arranged upon the outside of a furnace and heated by means of a steam-jacket in conjunction with a jet of steam entering the retort with the oil has been employed in connection with a pipe extending 60 from near the bottom of the retort to the passage of a nozzle projected into the fire-chamber, which pipe is necessarily used to conduct into the furnace the liquid and heavier portion of the hydrocarbon, which by the employment of steam alone cannot possibly be va- 65 porized.

Numerous hydrocarbon-furnaces have been provided which require a special construction 70 of the furnace itself; but to avoid this is one of the principal objects of my invention, which is attained by providing attachments which may be secured upon any furnace in which coal or other carbonaceous fuel is employed 75 for supplying in the requisite proportions one or more jets of hydrocarbon, steam, and air combined.

Hydrocarbons—such, for instance, as crude petroleum—contain about eighty-four per 80 cent. carbon, fourteen per cent. hydrogen, and two per cent. oxygen, and the advantages of their employment as fuel in furnaces may be understood by a comparison of their heating effect due to the excess of carbon over distilled 85 oils, in which there is less carbon and more hydrogen, and when practical experiments have demonstrated that the calorific power of these distillates, which contain 71.7 per cent. carbon and 28.2 hydrogen, would equal fifteen 90 thousand four hundred and sixty heat units, or an evaporative effect of about twenty-eight against 14.9 for the best coal. Crude petroleum conducted continuously into a red-hot retort is decomposed into a rich gas, the main constituents of which are light and heavy carbureted 95 hydrogens, which, burned with the active constituents of air, is attended with the evolution of great heat. Now, by passing a current of air of proper proportions over or through these 100 carbureted hydrogens, the air becomes so saturated with the vapors as to form a highly-in-

flammable mixture, which readily combines with the rising volatile hydrocarbons in the furnace, producing a perfect ignition of all the gases of the fuel employed. But to render the use of hydrocarbon liquids successful in a furnace, it is requisite not only that such liquids should be completely vaporized, but the vapors raised to a very high degree of heat and rapidly combined with proper proportions of air and the hydrogen of steam prior to entering the fire-chamber, and when so combined fully expanded and forcibly injected into the fire-chamber in such a manner as to be spread in a thin sheet over and in close proximity to the bed of burning fuel therein. To attain these results are the objects of my invention, other objects being to provide certain details of construction, hereinafter described, and shown in the accompanying drawings, in which—

Figure 1 is a perspective of a front end of a steam-boiler furnace, and also a similar view of a hydrocarbon-reservoir and its connection with a furnace embodying my invention; Fig. 2, an enlarged perspective of the hydrocarbon-reservoir; Fig. 3, a side elevation of an enlarged detail of the same; Fig. 4, a vertical detail of the furnace, showing the steam and air injector and hydrocarbon-retort in side elevation; Fig. 5, a similar view on an enlarged scale; Fig. 6, a section of the retort detached; Fig. 7, a top plan view of the retort; Fig. 8, a similar view of a modified form of the same; Fig. 9, a front end elevation of Fig. 8, and Fig. 10 a side elevation of the same.

Similar letters of reference indicate the same parts in the several figures of the drawings.

My invention is hereinafter described as applied to the ordinary and commonly-used steam-boiler furnace, in which the boiler extends longitudinally of the furnace and in a horizontal plane, said furnace being provided with grate-bars for coal or other solid carbonaceous fuel, and arranged in a plane below a bridge-wall, in the rear of which is a combustion-chamber, the usual doors being provided for access to the fire-chamber and ash-pit, as indicated by Figs. 1, 4, and 5, but is also adapted to be used in connection with locomotive or marine boilers, or any construction of furnace provided with a combustion or fire chamber, whether or not hydrocarbons are burned to the exclusion of solid fuel.

In carrying out my invention the devices preferably employed for injecting the steam and air are similar to those shown and described in United States Letters Patent No. 241,153, granted me May 10, 1881, and herein best shown in Fig. 5, in which C represents an inlet-pipe extending through the front wall in a horizontal plane above the grate-bars, and preferably just above a bed of burning fuel, and has tapped upon its outer and projecting end a globe "vacuum-chamber," D, opening into and extending in a vertical line from which is an air-supply pipe, E, the mouth of which pipe may be partially closed by a hollow cone,

F, the apex of which projects into the air-supply pipe, and serves to diminish the friction and hence the noise of the inrushing air.

Globe D is preferably closed at its top by a removable cap, G, providing access to the globe for removing obstructions, and has projecting therein a steam-nozzle, H, arranged in a horizontal plane in line with the inlet-pipe, 75 and extending beyond the center of the globe, and is connected with a steam-supply pipe, I, which preferably leads from the dome, where the steam is at its highest and dryest temperature in the boiler.

Between the globe and the furnace-wall is an oil-nozzle, J, which projects through the inlet-pipe C at a right angle to the steam-nozzle, and preferably so that as the oil escapes therefrom it will be in a plane with the steam-jet, and as near thereto as practically consistent with attaining the best vaporizing effects of the steam and avoiding the chilling effects of the inflowing air. The oil-nozzle is removably secured in a stem of suitable construction, and is tapped on an end plate supporting a glass tube, K, forming a sight-feed for the oil as it passes from a nozzle, L, removably seated in the upper plate of the glass tube, to the oil-nozzle J, said nozzle L having its butt tapped in an oil-supply pipe, M, in which is a globe-valve, N, of ordinary construction, adapted to cut off the supply of oil to the oil-nozzle J, and hence its flow through the sight-tube. Any number of these combined steam, air, and hydrocarbon feeds may be arranged upon a furnace, and at any point or points desired, whether in front, at the side, or rear, or all, as the exigencies of the furnace may require. These several feeds are supplied with steam 105 from a single supply-pipe, b, by means of a head, c, and so, also, the several oil-nozzles are supplied by a head, d, connected with the several nozzles, suitable stop-cocks or valves—such as valve N—being employed for cutting 110 off the supply of oil or steam to any one nozzle without obstructing the flow to one or more of the other nozzles, as desired; and in order to obtain steam at as high a temperature as possible, the supply-pipes b and c may be connected with a convolution of pipe arranged 115 in the fire-chamber and incased in fire-clay, or in the walls thereof, as indicated by their position to the right of Fig. 1, and thereby superheat the steam supplied to the feed.

The supply of oil is preferably furnished from a cylindrical tank, O, supported upon suitable brackets elevated sufficiently to not afford an obstruction in the vicinity of the furnace, and removed a sufficient distance therefrom to prevent the heat of the furnace seriously affecting its contents, said reservoir being connected with the head D' by a pipe, e, and with a suitable valve or cock, f, for regulating the flow of oil from the tank. At one 130 end of the tank, and vertical thereto, is a glass gage-tube, P, provided with suitable marks or numbers for indicating the capacity and contents of the reservoir, which it is enabled

to do through its connection by pipes *g h* with the upper and lower portions, respectively, of the reservoir, which is also provided at its top with a filling-pipe, *Q*, and an air-vent, *R*, as shown in Fig. 2, pipe *h* being provided with a cock, by means of which connection with the oil-feeds of the furnace may be made by a pipe, *i*, (see Fig. 3,) as well as or independently of the pipe *e*.

10 A reservoir constructed and arranged as above described is a convenient means for holding the oil-supply; but other means or constructions may be employed, as desired or adapted for the particular locality in which the furnace is employed.

15 So far as now described, means are provided for supplying the fire or combustion chamber with, as has been practically demonstrated, proper proportions of air and superheated steam, and also with a regulated supply of oil; but, as before intimated, steam is capable of vaporizing only the lighter portions of the oil or other hydrocarbons, and hence with this construction the heavier portions of the hydrocarbons would be thrown into the furnace in a liquid form, and thereby result in a waste 20 of the hydrocarbons, a dense smoke, and other unignited noxious gases, and a corresponding loss of heat. To avoid these objections, and 25 to not only vaporize the heavier portions of the hydrocarbons, but to raise such vapors to a very high temperature and correspondingly expand them, I provide a retort, *S*, of peculiar construction, tapped upon the inner end of the 30 supply-pipe *C*, and exposed to the heat of the fire or combustion chamber, which retort is the essential and important feature of my invention, the main object of which is to inject 35 into the fire or combustion chamber of a furnace a jet containing the proper proportions of steam, air, and hydrocarbon vapors at a high temperature with force and rapidity—a result not possible to attain without the employment 40 of devices embodying my invention, though, perhaps, materially varying in structure and 45 arrangement.

50 Retort *S* consists of an oblong vessel made of iron, fire-clay, or other suitable material, closed at its extremities, and projecting more or less below the plane of the inlet-pipe, so as to form a receptacle of a depth sufficient to catch the liquid portions of the hydrocarbons as they are forced inwardly toward the furnace by the steam and air, and is provided on 55 its outer face and toward its top with an elongated slot, *k*, forming an outlet for the combined jet.

The slot *k* is preferably straight and in a horizontal plane, but may be in the arc of a circle, and is of such dimensions that the jet will enter the furnace in a sheet, in which form it is best adapted to be quickly and thoroughly ignited.

60 As shown in Figs. 5 and 6, the retort is enlarged at its upper end, in which enlargement the slot is made; but I do not limit myself to this special construction of the retort, although

it has the advantage of providing an enlarged chamber for and adjacent the point of exit of the hydrocarbon vapors as they rise and are 70 expanded in the retort. It will also be observed in Fig. 5 that the slot is in a plane above the center of the inlet; but it may be in the same plane, although the advantage of its elevated position is to effectually prevent the 75 liquid hydrocarbon in the inlet-pipe being carried directly through the slot in the retort to the fire-chamber.

To remove obstructions from the retort a plug, *l*, is removably secured in its bottom, and 80 to avoid any liability of the retort being burned out, owing to its necessarily-exposed position in the furnace, it may be partially or wholly protected by fire-brick or other suitable covering, if desired.

85 Another form of device for vaporizing the heavier portions of the hydrocarbons is shown in Figs. 9 and 10, and consists of a nozzle, *T*, resembling in form the upper portion of the retort—that is to say, the nozzle is enlarged so 90 as to form a receptacle for catching and vaporizing the liquid hydrocarbons, and a chamber adapted to permit the expansion of the vapors thereof. These nozzles are adapted to be employed where hydrocarbons are used in small 95 quantities, or when they consist only of lighter portions—such, for instance, as refined petroleum—and when it is desirable to employ jets in numbers exceeding those designed to be employed with the retort; or they may be used 100 in a furnace with retorts. In other words, these nozzles embody my invention and produce the same results as retorts, only in a less degree, and serve to show the modifications to which my invention is subject without departing 105 from the spirit thereof.

110 Among the advantages of my invention, so far as relates to the retort, are that it may be attached to any ordinary furnace without materially obstructing the fire-chamber; that the heat of the furnace, when in operation, is always sufficient to heat the retort to the required degree; that it is sure to catch all liquid portions of the hydrocarbons dripping from the inlet-pipe; that no hydrocarbons can 115 escape therefrom except in the form of a vapor at a very high temperature; and that it provides for a substantially direct feed of the combined jet into the furnace, so that the force of the steam is fully utilized for forcing the 120 jet into the furnace, and of effecting a rapid and effective combination of the required proportions of steam and air and hydrocarbon vapors before entering the furnace, to produce the best results.

125 By employing the retort in connection with my globe vacuum-chamber all of the advantages common to that device for supplying air and steam serve to render the employment of the retort more effective—as, for instance, the continuous supply of a dense stream of pure air with a direct and given amount of steam, and the temperature of this air raised by the radiation of heat from the walls of the cham-

ber, in addition to that of steam, and directing this combined jet with all its force against the inflowing stream of hydrocarbon, are powerful auxiliaries to the functions of the retort in producing the best results; and, in fact, I am not aware of any other construction by which combustion so complete can be attained. Whether or not the retort is employed in connection with this particular construction, the gases are always greatly expanded in the retort before their escape, and in consequence of this expansion they are thrown by their own volition with an increased force into the fire-chamber, and are correspondingly and uniformly spread over its entire area; and in this connection it may be added that the retort is so effectual in its operation that no residuum of any kind remains therein, as has been demonstrated by actual experiment.

20 Having described my invention, what I claim, and desire to secure by Letters Patent, is—

1. The method of utilizing hydrocarbon liquids for heating purposes, the same consisting in forcing said liquid by means of steam into a retort heated by the furnace, in which retort the hydrocarbons rise and escape only in a vaporous form to the fire-chamber, as hereinbefore set forth.
2. The method of utilizing hydrocarbon liquids for heating purposes, the same consisting in forcing said liquid by and in conjunction with steam and air into a retort heated by the furnace, in which retort the hydrocarbons are vaporized and rise in their escape to the fire-chamber, substantially as described.

3. The method of utilizing hydrocarbon liquids for heating purposes, the same consisting in forcing said liquid by means of steam into a retort heated by the furnace, in which retort the hydrocarbon vapors rise and escape in a sheet-like form into the fire or combustion chamber, substantially as described.

4. The combination, with a steam and air inlet pipe of a furnace, of a hydrocarbon-retort secured to the inner end of said pipe and projecting below the plane of the same, said retort being provided toward its upper end with an outlet for the escape of the hydrocarbon vapors generated therein, substantially as described.

5. The combination, with a steam and air inlet pipe of a furnace, of a hydrocarbon-retort secured to the inner end thereof and projecting below the plane of said pipe, said retort being provided toward its upper end and in a plane above the center of the inlet-pipe with an outlet for the escape of the hydrocarbon vapors, substantially as described.

6. The combination, with the retort, the inlet-pipe, the globe vacuum-chamber, and means, substantially as described, for supplying steam and air to the same, of an oil-nozzle opening in the inlet-pipe at a point between said retort and chamber, and means for supplying the oil, all substantially as described.

ORLAND D. ORVIS.
